LOCOMOTIVE TENDER

Frank P. Roesch, Chicago, Ill., assignor to The Standard Stoker Company, Incorporated, a corporation of Delaware

Application April 6, 1939, Serial No. 266,319

6 Claims. (Cl. 105—234)

This invention relates to railway rolling stock and particularly to locomotive tenders provided with stoker conveyor mechanism.

An object of the invention is to provide a novel tender and stoker construction which will permit convenient installation of the stoker with a minimum of labor and expense and in which the stoker takes up a minimum of the water space of the tender.

Another object of the invention is to provide a tender and stoker construction of the type described in which convenient access may be gained to the various parts of the stoker from the fuel bin of the tender for purposes of inspection, repair and replacement.

Another object of the invention is to provide an improved construction and relation of parts in the tender for the lubrication of the stoker drive mechanism.

Another object of the invention is to provide a novel stoker drive, the construction of the drive and the arrangement thereof with the stoker providing a more compact unit and providing for convenient assembling and disassembling of the parts thereof.

Still another object of the invention is to provide an improved tender underframe of the water bottom type constructed to afford a maximum of strength, to provide an unobstructed bottom surface making it conveniently available for application of air compressors, piping and other necessary appurtenances, and to provide a maximum of water space.

Other objects and advantages of the invention reside in the novel construction of parts and the combination and relation of elements as will appear from the following description and claims when read in connection with the accompanying drawings, in which

Figure 1 is longitudinal vertical section on the irregular line 1—1 of Figure 2 through the novel tender underframe and a portion of the superstructure, with a stoker installed therein and shown in elevation;

Figure 2 is a sectional view taken on the line 2—2 of Figure 1;

Figure 3 is a fragmentary plan view through the forward portion of the tender showing the stoker applied thereto, parts being broken away;

Figure 4 is a longitudinal vertical central section through the forward portion of the tender with the stoker applied thereto and shown in similar section;

Figure 5 is a sectional view taken on the line 5—5 of Figure 4;

Figure 6 is a sectional view taken on the irregular line 6—6 of Figure 5;

Figure 7 is a sectional view taken on the line 7—7 of Figure 4;

Figure 8 is a sectional view taken on the line 8—8 of Figure 4;

Figure 9 is a sectional view taken on the line 9—9 of Figure 4, and

Figure 10 is a sectional view taken on the line 10—10 of Figure 4.

In the drawings, the tender is designated as a whole by the letter T and includes the underframe 10 upon which is mounted the superstructure or tender body portion.

The body portion includes a fuel bin 12 and the water compartment 13 separated by partition plates including the fuel bin floor 14, the rear slope sheet 15 and the side walls 16 and 17.

The fuel bin floor 14 is provided with a longitudinal centrally disposed cut out or opening 18, 20 extending substantially the entire length of the fuel bin floor. An open mouth trough 19, disposed in the water compartment 13, is arranged to receive fuel from the bin 12 through the opening 18 in the floor thereof. The upper marginal 25 sides of the trough 19 are provided with the outwardly extending flanges 20 and 21, respectively, overlapping the fuel bin floor 14 adjacent the marginal sides of the opening 18 therein, whereby the trough 19 is supported by the fuel bin 30 floor.

The rearward portion of the longitudinally extending opening 18 is laterally enlarged, as at 22, best shown in Figure 3, to receive a casing or housing 23, which is disposed in the water compartment 13 at the rearward end of and in communication with the trough 19. The housing 23 is open at its upper end and a flange 24 extends outwardly from the upper marginal edge of the casing overlapping the fuel bin floor 14. The 40 open upper end of the housing 23 is provided with a removable cover 25 providing access to the interior of the housing 23 from within the fuel bin 12. The front wall 26 of the housing 23 is pro-

vided with an opening conforming to the shape 45 of the trough 19 and a flange 27 extending outwardly from the marginal edge of the opening in the housing front wall 26 overlaps the outer surface of the rearward end of the trough 19.

The rearward end of the trough 19 is open providing communication between the trough and the housing 23. A weld 28 effects a rigid and water tight connection between the trough 19 and the flange 27 of the housing 23. The trough 19 and housing 23 can be installed in position as 50 55 55

a unit, after which the flanges 28 and 29 of the trough 19 and the flange 24 of the casing are secured to the fuel bin floor 14, by the welds 29, 30 and 31, respectively, providing a water tight seal between the water compartment and the fuel bin.

- 5 The front wall 32 of the water compartment is cut out at 33 following the contour of the trough 19, permitting insertion of the latter, after which the front wall 32 and the trough 19 are welded 10 together, as at 34, providing a water tight seal. The trough 19 extends a short distance forward of the front wall 32 and has a transversely extending plate 35 rigidly secured to the front end thereof, as by a weld 36. The plate 35 is provided 15 with a circular opening 37 forming a passage to the interior of the trough 19. A hollow ball casting 38 is provided with a short tubular portion 39 registering with the opening 37 in the plate 35 and bolts 40 passing through the flange 20 41 projecting outwardly from the tubular portion 39 rigidly secure the ball casting 38 to the plate 35. The hollow spherical portion 42 of the ball casting 38 is received in the spherical clamp portion 43 of the conduit 44 which extends forwardly 25 to the locomotive (not shown). The ball and clamp connection provides universal movement between the tender unit of the stoker and that portion leading forward to the locomotive when the locomotive and tender round curves or pass 30 over switches and turntables.

35 A screw conveyor 45 is disposed in the trough 19 and extends forwardly into the ball casting 38 through the opening 37 in the plate 35. At its forward end with the hollow spherical portion 42, the screw conveyor 45 is universally connected at 46 with a screw conveyor 47 housed within the conduit 44. A crusher member 48 is rigidly secured to the inner side of the plate 35 and arches over the screw conveyor 45, cooperating there- 40 with to reduce the large lumps of fuel to a size suitable for firing.

45 A plurality of transversely extending plates 49 are disposed in the water compartment 13 and are secured in any suitable manner at their respective upper and lower ends to the under side of the fuel bin floor 14 and the tender under-frame 10, respectively. The plates 49 are recessed as at 50 to receive the trough 19. These plates serve as water baffles and also as additional 50 supports for the trough 19 by means of the angles 51 which are securely attached to the plates 49 and fit closely against the sides of the trough 19.

55 Fuel from the fuel bin 12 enters the trough 19 through the opening 18 in the fuel bin floor 14. A plurality of plates 52 normally form a closure for the open mouth trough 19 and are arranged to be successively slid forwardly to uncover successive portions of the opening 18. The plates 60 52 are mounted in the guides 53 which are secured by the welds 54 to the upper inner marginal sides of the trough and are coextensive therewith. A depending plate-like member 55, secured in any suitable manner, as by a weld, to the forward end of the cover 25 of the housing 23, forms a stop member for the slide plates 52.

65 The drive mechanism for the screw conveyors 45 and 46 includes a gear casing 56 secured within the housing 23 by bolts 57 through the lugs 70 58 and 59 formed with the gear casing 56 and housing 23, respectively. The gear casing 56 is provided with a removable cover 60. A gear 61, disposed within the gear casing 56, a keyed on a shaft 62 journaled in the bearing 63 and 64 75 formed with the gear casing 56 and cover 60, re-

spectively. A drive connection of any suitable design is provided between the adjacent ends of the shaft 62 and the screw conveyor 45. A drive shaft 65 extends longitudinally through the trough 19 along the upper portion of the trough 5 sidewall.

The drive shaft 65 includes a rearward shaft portion 66 journaled in the bearings 67 and 68 of the gear casing 56 and cover 60, respectively, and a forward shaft portion 69 journaled in a bearing 70 which extends through an opening 71 in the plate 35. The bearing 70 is rigidly secured to the plate 35 by means of bolts 72 extending through the plate 35 and flange 73 which is formed with the bearing 70 and fits closely 15 against the plate 35. The drive shaft 65 also includes a tubular shaft member 74 coupled at its opposite ends with the forward shaft portion 69 and the rearward shaft portion 66 by the sleeves 75 and 76, respectively. A suitable number of 20 longitudinally extending keys 77 provide against relative rotation between the sleeves 75 and 76 and the adjacent ends of the tubular shaft member 74 and the shaft portions 66 and 69. Suitable gearing (not shown) is mounted on the part 25 of the rearward shaft portion 66 within the gear casing 56 and is in driving engagement with the gear 61 for operating the screw conveyors 45 and 47.

30 A collar 78 is secured to the forward shaft portion 69 by means of a threaded pin 79 and fits closely against the rearward end of the bearing 70, thereby preventing forward movement of the shaft portion 69. The sleeves 75 and 76 are normally prevented from moving longitudinally 35 along the tubular shaft member 74 by cotter keys 80 and 81, which are inserted through the shaft member 74 adjacent the ends of the sleeves 75 and 76, respectively.

With this coupling arrangement it will be seen 40 that the gear casing 56, the tubular shaft member 74 and the bearing structure 70 can be separately removed in a very simple and convenient manner. Thus, by removing the cotter pin 81 and sliding the sleeve 75 forwardly along the 45 tubular shaft member 74, the gear casing 56 may be removed; by withdrawing the cotter pin 80 and sliding the sleeve 75 rearwardly along the tubular shaft member 74, the bearing structure 70 may be removed; and by removing both cotter 50 pins 80 and 81 and sliding the sleeves 75 and 76 over the tubular shaft member 74, the latter may be removed without disturbing the bearing structure 70 or the gear casing 56.

55 One end of a drive shaft 82 leading from the stoker engine (not shown) is mounted in a bearing 83 formed with the sprocket casing 84. The sprocket casing 84 is rigidly secured to the plate 35, as by bolts 85, and is offset from the bearing structure 70. A sprocket 86 is mounted on the 60 forward end of the shaft portion 69 and a second sprocket 87 is mounted on the rearward portion of the drive shaft 82, and a sprocket chain 88 passing over the sprockets 86 and 87 provides a drive connection between the shaft 82 and shaft 65 portion 69.

65 With a drive arrangement such as that described, the drive shaft 65 can be disposed within a trough of usual width and the drive connection between the shaft leading from the stoker engine and the shaft leading back to the gearing at the rear of the trough does not interfere with the enlarged universal connection between the stoker conduits at the forward end of the tender.

70 The tender deck or shoveling platform 89 is 75

raised above the level of the fuel bin floor 14 so that the top surface thereof is flush with the top surface of the flanges 20 and 21 of the trough 19. The shoveling platform 89 is cut back or recessed, as at 90, to fit around the trough flanges 20 and 21. Rigidly secured to the underside of the shoveling platform 89 and in alignment with the guides 53 are the guides 91 in which the foremost of the slide plates 52 can 10 slide beneath the shoveling platform 89. The rearward end of the shoveling platform 89 is provided with a centrally disposed recess 92 arranged to register with the opening 93 in the rearward portion of the foremost slide plate 52 15 when it is drawn forwardly beneath the shoveling platform 89. The recess 92 thus provides for access to the slide plate when it is beneath the platform 89, by permitting insertion of a hook therethrough into the opening 93 of the slide plate.

Lubricant is supplied to the gear casing 56 by a supply pipe 94 extending rearwardly from the forward end of the tender through the trough 19 at that side thereof opposite the drive shaft 25 65. The pipe 94 rests loosely in a casing 95 formed in any suitable manner, as by an angle iron rigidly secured to the inner surface of the trough side wall. The forward end of the pipe 94 extends through the plate 35 and turns laterally, opening 30 upwardly at a point just below an opening 96 in the shoveling platform 89.

The tender is provided with a novel underframe 10 of the "water-bottom" type preferably formed of a one-piece casting. The underframe 10 comprises the side sills 100 and 101, the end sills 102 and 103, a substantially horizontal bottom web 104, and an upper web 105 provided with a plurality of openings 106 communicating with the water compartment 13 permitting the interior 40 of the underframe 10 to be used as additional water carrying space. A pair of truss members or center sills 107 and 108 extend longitudinally within the underframe from one end sill to the other and vertically from the bottom web 104 45 to the upper web 105. The bottom web 104 is provided at each side of the bolster structures 109 and 110 with the upwardly extending depressions 111 and 112, respectively, serving to accommodate the truck wheels.

The upper web 105 extends upwardly from each end sill and also from each side sill in the form of an upwardly bowed web. In such a construction, the vertical height of the truss members or center sills 107 and 108 is increased, providing a structure of increased strength and permitting the other parts of the underframe such as the side sills, bottom and upper webs 104 and 105 to be made lighter. By having the upper web bowed, 55 the lower web may be maintained substantially horizontal thereby leaving the underside of the lower web free for the various tender appliances. In such constructions where the strengthening members depend from the underside of the lower web, they cannot extend the entire length of the tender because of the bolsters for the trucks.

In the present construction however, the center sills 107 and 108 extend the entire length of the underframe, and their increased height made 60 possible by the bowed construction of the upper web 104, give added strength to the underframe. This added strength is obtained without decreasing the water carrying capacity of the tender and without obstructing the under side of the lower 70 web 104.

I claim:

1. In a tender having a fuel compartment and a water compartment, a floor for said fuel compartment, said water compartment extending beneath said floor, said floor having a longitudinally elongated centrally disposed opening, a stoker trough arranged to receive fuel from said bin, said trough having laterally projecting flanges overlapping said floor adjacent the marginal sides of the opening therein, a screw conveyor mounted in said trough, a housing at the rear of and communicating with said trough, said housing having an outwardly extending flange overlapping said floor adjacent the marginal edges of the opening therein, the upper end of said housing opening to said fuel bin, a removable cover for said last named opening, and drive mechanism in said housing operatively connected with said screw conveyor, the outer surface of said trough and said housing contacting the water in said water compartment.

2. In a tender having a fuel compartment, a floor for said fuel compartment, said floor having a longitudinally elongated centrally disposed opening, a stoker trough arranged to receive fuel from said bin through said opening, a screw conveyor mounted in said trough, a housing at the rear of and communicating with said trough, the upper end of said housing opening to said fuel bin and having an outwardly extending flange overlapping said floor adjacent the marginal edges of the opening therein, and drive mechanism in said housing operatively connected with said screw conveyor, said drive mechanism being removable from said housing through its open upper end into said fuel compartment.

3. In a tender having a fuel compartment, a floor for said fuel compartment, said floor having a longitudinally elongated centrally disposed opening, a stoker trough arranged to receive fuel from said bin, said trough having laterally projecting flanges overlapping said floor adjacent the marginal sides of the opening therein, a screw conveyor mounted in said trough, a housing at the rear of and communicating with said trough, said housing having an outwardly extending flange overlapping said floor adjacent the marginal edges of the opening therein, the upper end of said housing opening to said fuel bin, and drive mechanism in said housing operatively connected with said screw conveyor.

4. In a tender having a fuel bin, a stoker trough arranged to receive fuel from said bin, said trough being generally V-shaped in cross section, a screw conveyor in the lower restricted portion of said trough, drive mechanism at the rear of said trough operatively connected with said screw conveyor, and a drive shaft within and at one side of said trough above the plane of the upper peripheral edge of said screw conveyor extending forwardly from said drive mechanism through the forward end of said trough.

5. In a tender having a fuel bin, an upwardly flaring stoker trough arranged to receive fuel from said bin, a screw conveyor in the lower portion of said trough, drive mechanism at the rear of said trough operatively connected with said screw conveyor, a tubular member communicating with and extending forwardly from the forward end of said trough, said tubular member being in axial alignment with said screw conveyor and having a spherical enlarged forward portion and a restricted rearward portion, and a drive shaft within and at one side of said trough above the plane of the upper peripheral edge of said screw

conveyor extending forwardly from said drive mechanism through the forward end of said trough, the projecting portion of said shaft being at one side of and above the restricted portion of said tubular member.

5. In a tender having a fuel bin, an upwardly flaring stoker trough arranged to receive fuel from said bin, a screw conveyor in the lower portion of said trough, drive mechanism at the rear 10 of said trough operatively connected with said screw conveyor, a tubular member communicating with and extending forwardly from the forward end of said trough, said tubular member being in axial alinement with said screw conveyor and

having a spherical enlarged forward portion and a restricted rearward portion, a drive shaft within and at one side of said trough above the plane of the upper peripheral edge of said screw conveyor extending forwardly from said drive mechanism through the forward end of said trough, the projecting portion of said shaft being at one side of and above the restricted portion of said tubular member and terminating short of the enlarged portion thereof, a second shaft offset laterally 10 from and extending forwardly from the front end of said first named shaft, and a drive connection between the adjacent offset ends of said shafts.

FRANK P. ROESCH.
